UNITED STATES PATENT OFFICE.

GEORGE S. HILL, OF STRAFFORD, NEW HAMPSHIRE, ASSIGNOR, BY MESNE ASSIGNMENTS, TO UNITED SHOE MACHINERY CORPORATION, OF PATERSON, NEW JERSEY, A CORPORATION OF NEW JERSEY.

SEWING-MACHINE.

1,389,000.

Specification of Letters Patent. Patented Aug. 20, 1921

Original application filed June 19, 1916, Serial No. 104,449. Divided and this application filed May 11, 1917. Serial No. 167,933.

To all whom it may concern:

Be it known that I, GEORGE S. HILL, a citizen of the United States, residing at Strafford, in the county of Strafford and State of New Hampshire, have invented certain new and useful Improvements in Sewing-Machines; and I do hereby declare the following to be a full, clear, and exact description of the invention, such as will enable others skilled in the art to which it appertains to make and use the same.

The invention relates to thread controlling mechanism for sewing machines.

15 The present application is a division of application Serial No. 104,449, filed June 19, 1916.

1910. The object of the invention is to provide novel and improved devices for controlling the needle thread between the needle bar and the thread supply which are simple in construction and efficient in operation, and which are well adapted for coöoperating with a needle mechanism driven at high speed. To these ends the invention comprises the features of construction and combinations of parts hereinafter described and referred to in the claims.

The invention will be readily understood from an inspection of the accompanying drawings and the following detailed description of the mechanism illustrated therein.

In the drawings, Figure 1 is a front elevation, partly in section, showing so much of a buttonhole sewing machine as is necessary to illustrate the application of the present improvement thereto, and Fig. 2 is a detail side elevation showing the thread controlling devices, the tension device being removed to show the parts behind it.

40 In the drawings the invention is shown as embodied in a buttonhole making machine comprising in general a cutter which operates to cut the buttonhole slit after the completion of the sewing, a reciprocating and laterally moving work clamp, and a sewing mechanism which is rotated during the sewing about the eye of the buttonhole, and which comprises a vertically reciprocating and laterally vibrating upper needle and co-operating looping and loop spreading devices arranged below the work.

In the machine shown the work clamps, indicated at 2, are mounted upon the work

supporting plates 4 which are pivoted on a longitudinally and laterally moving clamp 55 carriage 6. The clamps are automatically closed at the beginning of the sewing, and are automatically opened after the completion of the buttonhole, by mechanism which forms no part of the present invention, and which need not be described. The button-hole slit is cut at the completion of the sewing by a cutter indicated at 8 which is operated by a cam on the main cam shaft of the machine. The work is carried by the clamp 60 over a throat plate 10 mounted on a turret 12 which carries the under looping and loop spreading mechanism. The looping and loop spreading mechanism comprises two pairs of opposed looper and loop spreading 70 points indicated at 14 which are arranged to reciprocate below the throat plate, and are constructed to alternately enter the loops thrown out by a vertically reciprocating and laterally vibrating upper needle 16, and co-operate with the needle in forming the well-known Humphrey stitch. The needle 16 is eccentrically mounted in a hollow needle bar 18 which reciprocates in a carrier sleeve 20. The carrier sleeve is reciprocated through a 80 bell crank lever indicated at 22, the horizontal arm of which is connected by a ball joint with the upper end of the sleeve and the vertical arm of which is indicated at 24. The lower end of the sleeve is moved laterally 85 during its reciprocation by a link 26, one end of which is connected to the sleeve, and the other end of which is connected with a pivot 28 on the rotary head 30. As the sleeve moves downward, the link acts to swing the 90 lower end of the sleeve and the needle bar toward the right, so that the needle bar will be in position for the depth stitch, and as the sleeve rises the link acts to swing the sleeve toward the left, so that the needle bar will be 95 in position to form the slit or edge stitch. The parts are so timed that the needle bar makes two reciprocations for each reciprocation of the carrier sleeve, so that the carrier will be moved to the right during one 100 reciprocation of the needle, and to the left during the succeeding reciprocation, and thus the needle will be vibrated to alternately form depth and edge or slit stitches. The needle bar is reciprocated by a crank 105 32 which is carried by a shaft 34 and is con-

nected to the needle bar by a link 36. The rotary head 30 in which the carrier sleeve and needle bar are carried, and the rotary turret 12 in which the looper mechanism is carried, are rotated in unison during the sewing about the eye of the buttonhole through shafts 38 and 40 and gears 42 and 44.

The upper needle thread passes from the eye of the needle up through a light tension device (not shown) mounted on the side of the needle bar, up through the hollow needle bar, and from the end of the bar it passes laterally under a thread guiding finger 46 to a tension device 48, from which it leads through suitable guides to the thread supply. The thread guiding finger 46 and the tension device 48 are arranged at one side of the needle bar, and the finger is so mounted that it may be adjusted vertically to vary the take-up action of the needle bar as it is retracted. In order to retain or hold the thread substantially taut during the downward stroke of the needle, and until the needle eye enters the work, a thread retainer 50 is arranged adjacent to the upper end of the needle bar when the bar is in retracted position, and is constructed to retain the thread until the thread is withdrawn therefrom by the downward stroke of the needle after its eye has entered the work and the needle is acting to carry a loop below the work. As shown, this thread retainer comprises a spring clip secured to the cap plate 52 which is removably attached to the head of the machine in front of the upper needle mechanism.

During the final upward movement of the needle bar the thread leading from the upper end of the needle bar to the guiding finger 46, or to the tension device, passes between the members of the clip, as indicated in the drawings. During the first part of the downward stroke of the needle bar, the thread retainer frictionally holds the thread so that the needle slides down the standing thread until its eye enters the work. This insures the proper control of the thread and holds it substantially taut between the preceding stitch and the tension device until slack thread is required for the formation of the needle loop below the work. As the eye of the needle enters the work, carrying a loop of thread with it, the pull on the thread withdraws it from the thread retainer, so that slack thread is provided between the upper end of the needle bar and the tension device for the loop carried below the work by the needle. During the upward stroke of the needle bar the upper end of the needle bar acts as a takeup to set the stitch, and thereafter draws thread through the tension device for the succeeding stitch. The

takeup action of the needle bar may be varied by vertical adjustment of the thread guiding finger 46, so that it will deflect the thread between the tension device and the upper end of the needle bar to a greater or less extent.

While it is preferred to employ the specific construction and arrangement of parts shown and described in embodying the invention in a machine of the type shown, it will be understood that this construction and arrangement are not essential to the broader scope of the invention, but may be varied or modified as found desirable or best suited to the construction of the machine in which it is to be embodied.

Having explained the nature and object of the invention, and specifically described one form of mechanism in which it may be embodied, what is claimed is:—

1. A sewing machine having, in combination, a vertically reciprocating upper needle bar, complemental under mechanism comprising looper and loop spreader points co-operating with the needle to form overseam stitches, a thread guide on the upper part of the needle bar, a thread guide at one side of the needle bar against which the thread is drawn by the needle bar during the latter part only of the upward stroke of the bar, and a stationary thread retainer arranged between the guides and constructed to frictionally hold the thread until withdrawn therefrom by the action of the needle eye on the thread, as the eye carries a loop of thread through the work.

2. A sewing machine having, in combination, a vertically reciprocating and hollow needle bar through which the upper thread passes, a thread guide at one side of the path of travel of the upper end of the bar against which the thread is drawn by the latter part only of the upward stroke of the bar, and a thread retaining clip between the guide and the upper end of the bar into which the thread is carried by the final upward movement of the needle bar and from which it is drawn by the action of the needle eye on the thread as the eye carries a loop of thread through the work.

3. A sewing machine, having, in combination, a vertically reciprocating hollow needle bar through which the upper thread passes, complemental under mechanism co-operating therewith to form overseam stitches, a tension device arranged at one side of the needle bar, a vertically adjustable thread guide under which the thread passes from the tension device to the upper end of the needle bar, and a thread retainer between the guide and end of the bar for retaining the thread until the needle enters the work.

GEORGE S. HILL.
